UNITED STATES PATENT OFFICE

CRAWFORD J. WALKER, OF INDIANAPOLIS, INDIANA, ASSIGNOR TO THE PROTECTU CORPORATION, OF INDIANAPOLIS, INDIANA

NONREADABLE CARBON PAPER

Application filed June 23, 1930. Serial No. 463,010.

This invention relates to the art of carbon paper, and particularly to means for concealing from view characters impressed upon a second sheet through the paper. In machine bookkeeping method as described in my U. S. 5 application for patent filed April 7, 1930, Serial Number 442,090, a carbon sheet is employed in part to cause an impression to be made thereby on a second sheet upon an impression being made on a first sheet, and in part to conceal from the operator's view 10 an impression made directly through the carbon paper on a part of the carbon paper and second sheet which may project beyond the side of the first sheet. The characters 15 impressed on that projecting second sheet through the heretofore employed carbon paper were easily read on the upper or uncoated side of the carbon paper even though the paper be black in color.

My invention provides a carbon sheet so formed that characters impressed directly thereon can not be read, and what is printed on a second sheet thereunder through the 25 carbon paper can only be ascertained by lifting the carbon paper therefrom to render the second sheet visible.

The single view in the drawing shows the obverse side of a sheet of carbon paper embodying my invention.

The sheet 10 is processed in the customary manner well known to those versed in the art to form the copying or coated reverse side 11. On the obverse side, I provide a 35 blind surface here shown as arranged in the two columns 12 and 13, one toward each vertical edge. This surface is produced by printing on the sheet the resultant design as produced by arranging horizontal rows 14 40 of non-consecutive letters across vertical rows 15 of non-consecutive letters of the alphabet. I employ all upper case letters and it is essential in both the horizontal and vertical rows that there be no spacing between the individual letters in adjacent rows above or below or on either side. Any letters or signs impressed upon this resultant 45 design are entirely blended into the maze of 50 lines so that it is impossible to read or de-

termine by observation, what letters or signs were impressed.

Contrary to what may be expected, a black surface under this design renders the impression thereon of characters somewhat visible 55 over and above the design, and I, therefore, employ a gray or white surface under the design. In bookkeeping, of course, the characters are with few possible exceptions not letters of the alphabet, so that there is the additional confusion of lines introduced when 60 figures are impressed upon the crossed rows of letters.

I claim:

1. A paper for preventing the reading of 65 characters impressed thereon including a transferring medium on one side, and on the other a plurality of lines produced by horizontal and vertical rows of upper case letters of an alphabet, the letters in each row 70 being adjacent the letters of the next row.

2. A paper for preventing the reading of 75 characters impressed thereon including a transferring medium on one side, and on the other a plurality of lines produced by horizontal and vertical rows of upper case letters of an alphabet, the letters in each row being adjacent the letters of the next row, the background of said surface being lighter than the said lines.

3. A non-readable carbon paper having a transferring medium on the reverse side, and a plurality of upper case letters of an alphabet on the obverse side, said letters being arranged in crossed rows with the letters in each row substantially contacting with the letters in the adjacent rows and one another.

4. A non-readable carbon paper having a transferring medium on the reverse side, and 90 a plurality of upper case letters of an alphabet on the obverse side, said letters being arranged in crossed rows with the letters in each row substantially contacting with the letters in the adjacent rows and one another, 95 said letters in each row being in non-consecutive order.

5. A non-readable carbon paper having a transferring medium on the reverse side, and 100 a plurality of upper case letters of an al-

phabet on the obverse side, said letters being arranged in crossed rows with the letters in each row substantially contacting with the letters in the adjacent rows and one another, said obverse side being lighter in color than the letters thereon.

6. A non-readable copying paper having a transferring medium on the reverse side and a plurality of characters on the obverse side, said characters being imprinted one over the other, the upper characters being angularly disposed in reference to the under characters.

7. A paper for the prevention of the reading of writing impressed thereon having a plurality of characters imprinted thereon in juxtaposition one over the other, each overlying character being angularly disposed in relation to the under characters.

10 20 In testimony whereof I affix my signature.
CRAWFORD J. WALKER.
